WALL MOUNTED SUPPORT FOR BABY NURSERY ACCESSORIES OR THE LIKE

Stuart S. Leopold, 600 Shore Road,
Long Beach, N.Y. 11561

Filed Feb. 7, 1975, Ser. No. 547,989

Term of patent 14 years

Int. Cl. D6—04

U.S. Cl. D6—131

FIG. 1

FIG. 2

FIG. 3

FIG. 4

FIG. 5

FIG. 6

FIG. 7

FIG. 1 is a prospective view of a wall mounted support for baby nursery accessories or the like showing my new design;

FIG. 2 is a front elevation view thereof;

FIG. 3 is a top plan view thereof;

FIG. 4 is a side elevation view taken from the left of FIG. 1;

FIG. 5 is a side elevation view taken from the right of FIG. 1;

FIG. 6 is a rear elevation view thereof; and

FIG. 7 is a bottom plan view thereof.

I claim:

The ornamental design for a wall mounted support for baby nursery accessories or the like, substantially as shown and described.
